EVAPORATOR COIL AND THE LIKE

John F. Furry, Waukegan, Ill., assignor to Out-board, Marine & Manufacturing Company, Waukegan, Ill., a corporation of Delaware

Application October 30, 1937, Serial No. 171,864

6 Claims. (Cl. 62—126)

This invention relates to improvements in evaporator coils and the like. The present application is a companion to the application of Stephen F. Briggs, Serial No. 105,001 filed October 10, 1936, entitled Refrigerating units.

It is the primary object of the present invention to provide an improved form of tube and an improved coil structure with particular reference to the use thereof in refrigerator evaporators. More particularly stated, it is my purpose to enable the several successive coils of an evaporator to be interlocked mechanically with each other, thereby avoiding the necessity of using jigs or solder or other coatings as a means of such connection.

The invention has particular utility where the tube from which the coil is made is constructed of a metal which neither requires any exterior coating nor, perhaps, is well adapted to receive such a coating.

Other objects of the invention will appear from the following disclosure.

In the drawing:

Figure 1 is a view in perspective of an evaporator coil made in accordance with the present invention.

Figure 2 is a view in end elevation of a completed evaporator, the circulatory connections thereto being fragmentarily illustrated.

Figure 3 is an enlarged detail view in cross section through a series of tube portions united in accordance with the present invention.

Like parts are identified by the same reference characters throughout the several views.

Those skilled in the art will appreciate that it is possible to make by extrusion tubes of the novel cross section clearly shown in Fig. 3, in which I have shown a tubular body portion 4 integrally provided at 5 with a continuous tongue 10 joined to the body portion by a narrow web 6, while at the opposite side of the body portion a similar web 7 supports the integrally formed continuous flanges 8 which are upset into interlocking engagement with the head 5 of the adjacent tubular body 4.

For many purposes it may be desired to connect in this manner a plurality of tubes whereof the interiors are not connected in series. In other words, the several passages 9 through the tubular body portions 4 of the tube structure shown in Fig. 3 may be wholly disconnected from each other or may be connected by headers or otherwise in any sort of a radiating or heat absorbing structure. For the purposes of the

present invention, however, it is preferred to use a single continuous tubular member formed throughout its length to provide the cross section shown in Fig. 3 and wound into a helix with its successive convolutions interlocked with each other as shown in Figs. 1 and 3.

A convenient metal to be used in the construction of such a tube is aluminum. Aluminum is suitable for use in a heat transfer device, it is readily extruded to make tubes of any desired cross section, it requires no plating or other finishing, and the means for mechanically connecting the successive coils as herein disclosed is greatly to be preferred over previously existing means of treatment.

When the tube is first extruded it is preferably so formed that the continuous flanges 8 are relatively widely separated as shown at the right at 8' in Fig. 3. Then when the tube is wound into a helix in accordance with the disclosure of Fig. 1 the continuous tongue 5 of each successive convolution can be forced into the contiguous groove provided by the open flanges 8' and thereafter the flanges may be pressed together by any desired means to engage the tongue with sufficient clamping pressure to maintain it interlocked therein.

The circulatory connections 10 and 11 may then be soldered into the ends of the evaporating coil and the mounting 12 provided to complete the evaporator. While there is nothing to preclude the dipping or other coating of such a coil, such dipping or coating is unnecessary and its absence facilitates heat transfer.

I claim:

1. In a device of the character described, the combination with a tube of helical form having successive contiguous convolutions, of means formed integrally with the sides of said tube and substantially continuous throughout said convolutions for mechanically interlocking successive convolutions with each other.

2. A heat transfer device comprising a tube wound in helical form to provide successive convolutions contiguous to each other, said tube having a tongue substantially continuous along one side thereof and a channel substantially continuous along the other side thereof, the tongue portions of successive convolutions being in interlocking engagement with the channel portions of contiguous convolutions.

3. In a device of the character described, a tube formed to constitute a helix having successive convolutions, said tube having oppositely ex-

- tending integral webs, one of said webs carrying an integral and substantially continuous tongue and the other of said webs being bifurcated to provide integral and substantially continuous flanges, the flanges of one convolution being formed into interlocking engagement about the tongue of an adjacent convolution, whereby to maintain said last mentioned convolutions interlocked mechanically to each other.
- 10 4. As a new article of manufacture, a tube comprising a hollow body portion, a plurality of webs projecting from said body portion and extending along said body portion, a headed tongue carried by one of said webs, and a pair of flanges carried by the other of said webs and open to receive the headed tongue of a tube of like cross section.
- 15 5. An extruded tube comprising a hollow body

greatly elongated as compared with its cross section and provided continuously along its sides with flanges having mutually hooked and curved means formed for interlocking engagement with each other and with the complementary flanges of like tubes.

6. In a device of the character described, the combination of a tube formed to constitute a helix having successive convolutions and integral flange means projecting from opposite sides 10 thereof, the flange means projecting from one of said sides having a hooked portion in interlocking connection substantially throughout said convolutions with the flange means projecting from the opposite side of the tube in contiguous 15 convolutions whereby to unite said convolutions mechanically to constitute a chamber.
